DRIVER'S GARMENT

Joseph R. Tricarico, Riverton, N. J.

Application November 13, 1951, Serial No. 17,357

Term of patent 3½ years

(Cl. D3—25)

To all whom it may concern:

Be it known that I, Joseph R. Tricarico, a citizen of the United States, residing at Lake View Motels, Route #25, Riverton, New Jersey, have invented a new, original, and ornamental Design for a Driver's Garment, of which the following is a specification, reference being had to the accompanying drawing, constituting a part hereof.

Fig. 1 is a front perspective view of the driver's garment, embodying the features of my new design;

Fig. 2 is a rear perspective view of the driver's garment.

I claim:

The ornamental design for a driver's garment, substantially as shown.

JOSEPH R. TRICARICO.
